UNITED STATES PATENT OFFICE.

RALPH A. SCHOENBERG, OF NEW YORK, N. Y., ASSIGNOR TO IDA S. ROSENHEIM, OF NEW YORK, N. Y.

MEANS FOR CONVERTING MOTION.

1,182,216.

Specification of Letters Patent.

Patented May 9, 1916.

Application filed January 5, 1910. Serial No. 536,548.

To all whom it may concern:

Be it known that I, RALPH A. SCHOENBERG, a citizen of the United States, and a resident of New York city, in the county and State of New York, have invented certain new and useful Improvements in Means for Converting Motion, the same being an improvement upon United States Patent No. 844,455, patented February 19, 1907, grant-
ed to Klein.

The following is a specification of my invention taken in connection with the accompanying drawings, which form a part of the same.

This invention relates to means for converting motion or mechanical movements and is adapted for universal application. Simply for the purposes of illustration I have shown one use of my invention applying it to an electric switch, but it is to be distinctly understood that my invention is not limited to this or any other particular use.

The accompanying drawings showing illustrative embodiments of this invention and in which the same reference numerals refer to similar parts in the several figures,—Figure 1 is a vertical sectional view through a mounting showing my invention in side elevation and used as an electric switch; Fig. 2 is a vertical sectional view through the mounting, which in this instance is preferably porcelain or some other insulating material, and a vertical section through the cartridge; Fig. 3 is a side elevation of my invention, parts being broken away and the nuts 64 omitted for purposes of better illustration; Fig. 4 is a vertical section substantially on line 4—4 of Fig. 3 with the spring 67 omitted; Fig. 5 is a plan view of a blank from which the cartridge is made; Fig. 6 is a plan view of the cartridge made from the blank shown in Fig. 5; Fig. 7 is an end elevation of the cartridge; Fig. 8 is a side elevation of the cartridge; Fig. 9 is a perspective view of one element of the locking device with which my invention is preferably, though not necessarily, equipped; Fig. 10 is a blank from which the nose piece or driving member is formed; Fig. 11 is a perspective view of the nose piece or driving member formed from the blank as shown in Fig. 10; Fig. 12 is a perspective view of one of the vertically reciprocating members which, in the form

shown in this invention, acts as a support for the driving member and a push button; Fig. 13 is a side elevation of one of the levers; Fig. 14 is a cross section through one of the nose pieces or driving members 60 showing the preferred form of elliptical spring; Fig. 15 is a detail plan view of the preferred form of driven member; Fig. 16 is a plan view of the blank from which the moving contact is preferably formed; Fig. 65 17 is a detail perspective view of the moving contact made from the blank shown in Fig. 16; Fig. 18 is a plan view of certain insulations; Fig. 19 is a plan view of a washer; Fig. 20 is a detail vertical section 70 showing a modified form of auxiliary spring; Fig. 21 is a detail view of a modification in which the moving contact is equipped with the locking device; and Fig. 22 is a detail sectional view on the line 75 23—23 of Fig. 21.

In the illustrative embodiments of this invention shown in the drawings, 1 (Figs. 3, 6, 7 and 8) is a support which for purposes of description, but with no idea whatever of limiting the invention, will be hereinafter referred to as a cartridge, it being distinctly understood that any suitable support for supporting the elements of my mechanical movement would come under the terms of my invention. This cartridge or support 1 80 I preferably make from the blank 2, (Fig. 5) which can be stamped or otherwise made quickly, cheaply and expeditiously from sheet metal or other material. This blank 90 2 has a bottom portion 3 and sides 4, 4 which are bent up from the bottom portion 3 along the dotted lines 5, 5 until the sides assume a position substantially at right angles to the bottom portion. The 95 ends 6, 6 are then bent along the lines 7, 7 the ends being oppositely disposed and each closing one end of the cartridge. The ears 8, 8 formed in the ends 6, 6 are then substantially bent at right angles to the sides 6, 6 to form bearings for screws or other securing means 9 (Fig. 2) which secure the cartridge and with it the contained mechanism to any suitable base such as a porcelain or other insulating base 10 (Fig. 105 2). The upper portion of the end pieces 4, 4 have preferably stamped in them at the same time that the blank is formed openings or apertures 11, 11 (Figs. 5 and 8) for the reception of a securing member or bridge 110

piece 12 (Figs. 1, 2, 4 and 20). This single securing member 12, which is also preferably formed of stamped sheet metal not only secures the two side members 4, 4 together, but it also serves to lock and securely hold within the cartridge the other elements as will be readily seen for instance in Fig. 2.

Within each side member 4 of the blank 2 (Fig. 5), I preferably provide segmental 10 slots 13, 13 and an aperture 14 at the center of the same circle of which the segmental slots 13, 13 are a part. Within these segmental slots 13, 13 and the apertures 14 I mount the preferred form of driven member 15 of my mechanical movement. This element may be formed in various ways provided it is made of two or more parts, as shown by way of example in Fig. 15.

In Fig. 15 I have shown the preferred 20 form of driven member which comprises two wings 16, 16 with an interposed separate pin 17. In this preferred form each wing is provided with a stepped recess 18, the larger openings 19, 19 being adapted to receive side levers 20, 20 (Figs. 3, 4 and 13), while one wall of the smaller portion 21 of the recess 18 moves upon the bearing surface 22 of the segmental slots 13, 13 (Figs. 4 and 5). This preferred form of driven member 15 is mounted in the cartridge by locating the axle or pin 17 within the apertures 14, 14 and the wings 16, 16 within the segmental slots 13, 13 so that they are supported by and move upon the bearing 30 surfaces 22, 22 of the cartridge as previously noted. Each end of the wings 16, 16 is provided with a threaded boss 23 which extends without the sides of the cartridge 4, 4 carrying, in this particular use of my invention, the moving contact 24 (Figs. 1, 4 and 17) in a manner hereinafter more fully described.

Within the cartridge 1, I also mount one or more driving members 25 (Figs. 2, 11 and 20) which bear upon and coöperate with the driven member 15. While I will describe and have illustrated two such driving members 25, it is to be distinctly understood that while such an arrangement is the preferred construction of my invention, my invention will operate with simply one such driving member. These driving members comprise a laterally movable rigid element and a contained resilient member such as a spring 26. For purposes of ready description this laterally movable element, with no idea of limiting the invention by using any narrow terminology will be hereafter referred to as a nose piece. This nose piece 50 is preferably formed from a single stamping from sheet metal or other material, making a blank 27 (Fig. 10). This blank is bent upon the line 28 to form the nose 29, the two ends being again bent on the lines 30, 30 60 to form the top and bottom 31, 32, the blank

being further bent upon the lines 33, 33 to form the cross sides 34, 34. Within this nose piece 29 I mount some resilient material which is preferably, though not necessarily, a coil spring 26. Preferably I make the coils 70 of this spring elliptical to enable me to get a strong resilient member within the rectangular interior of the nose piece 29 and one which is not apt to bend transversely to its length. The rear portion of this resilient member 26, whether it be a spring or other suitable medium, bears upon a vertically reciprocating member 35 which is also formed from a blank stamped from sheet metal or other material and bent up into the shape shown 80 in Fig. 12. This vertically reciprocating member may be actuated in various ways depending upon the use to which my mechanical movement is to be put. As I have shown my invention used to operate an electric 85 switch this reciprocating member 35 can be operated by a push button 36 which is formed of any suitable material and is provided with an aperture 37 for the reception of the upwardly extending member 38 which 90 is secured within the opening 37 in any suitable manner. It is to be understood, however, as noted, that this upwardly extending member 38 may be given various shapes and configurations and may be variously operated. When the member 35 is bent up from a blank to assume its proper shape as shown in Fig. 12, it is provided with a bottom 39 and a top 40, and a closed end 41. The bottom 39 and the top 40 of the vertically reciprocating member 35 serves to guide and hold the driving member comprising the laterally movable member or nose piece 29 and its resilient member such as the coil spring 26, the rear end of which bears upon 100 the closed end 41 of the vertically reciprocating member 35. It will, therefore, be readily seen that by this mounting the driving member 25 has a lateral movement with relation to the vertically reciprocating member 35, but that it is so held between the bottom and top 39 and 40, respectively, of the reciprocating member 35 that it has to move with it. As I have shown the button 36 secured to the vertically reciprocating 110 member 35, I will hereafter for purposes of ready description refer to this element 35 as a button-holder, but when using this term it is to be understood that any vertically reciprocating member is meant, whether or not it 115 is provided with a button such as 36 or given any other contour from that shown. This button-holding device 35, or vertically reciprocating member is preferably provided with an integral lug 42, and an ear 43 extending 120 on one side and an elongated ear 44 on the other side; this latter ear 44 performs in the device shown several functions being a part of the locking device, though for the purpose of the immediate description its first 130

function, as that of a guide, will at present only be referred to, for my invention will successfully operate without a locking device, which is preferably used but in some instances may be omitted.

5 In bending the ends 6, 6 of the blank 2 around to close the ends of the cartridge 1 their extreme ends 45, 45 do not touch the side members 4, 4 thereby forming guide slots 10 47, 47 oppositely disposed in the cartridge (Fig. 6) within which slides the lug 42 (Fig. 12) of the button-holder. It is to be understood of course that when two button-holders, or vertically reciprocating members are 15 used, the lugs 42 are placed upon their opposite sides to correspond with the opposed guide slots 47, 47 which would make the button-holders right and left. The ear 43 operates in and is guided by the slot 48 of the 20 side member 4 (Figs. 5 and 8). The opposed elongated ear 44 on the opposite side of the vertically reciprocating member or button-holder 35 moves in and is guided by the slot 25 49 in the other side member 4 (Figs. 5 and 6).

Mounted on the axle or pin 17 and therefore on the side of the cartridge or support 1, I preferably mount two levers 20, 20 (Figs. 3 and 13) one on each side of the 30 cartridge (Fig. 4), but it is to be distinctly understood that one such lever is sufficient for the successful operation of my invention. In the preferred construction of driven member, these levers, as noted, will 35 be located in the enlarged portion 19, 19 of the stepped recesses 18, 18 (Figs. 15 and 4.) Each arm of the lever is preferably provided with a notch 50 for the reception of the ears 43 and 44 (Fig. 3). It will be noted 40 that as these arms are guided in the respective guide slots 48 and 49, there must be relative movement between them and the levers. This is clear from Fig. 3 wherein one ear 44 is shown as bearing approxi- 45 mately in the notch or groove 50, while the corresponding ear on the other button-holder is shown bearing on the enlarged end 51 of the lever 20.

I have shown my invention for purposes 50 of illustration in connection with a double pole switch, though, of course, it would operate a single pole switch. For purposes of description the switch controlling one pole of the double pole switch illustrated will be 55 described, it being understood that the other pole operates in a similar manner. On the ends of the wings 16, 16 and on the axle 17 I mount (omitting the retarding plate) insulating disks 52, 52 (Figs. 4 and 18) provided with enlarged openings 53 of sufficient 60 length to take over the two wings 16, 16. Between these insulating disks 52, 52 I mount a smaller insulating disk 54 also provided with an enlarged opening 55, and on 65 this insulating disk 54 I mount the movable

contact of the switch. This movable contact may be formed in various ways and of various conducting materials. I preferably, though not necessarily, form it out of a blank 56 (Fig. 16) bending the blank at 57 70 to obtain the doubled movable contact 24 (Figs. 1, 4 and 17). It will be seen that by this construction each arm 58 and 59 is formed of two opposed spring members 60, 60 which receive between them the fixed 75 contacts 61, 62; the fixed contact 61 coöperating with the arm 58 and the fixed contact 62 coöperating with the arm 59 of the movable switch 24 (Fig. 1). This movable contact 24 and its insulating disks are secured 80 to the driven member 15 in any suitable manner such as by a washer 63 and nuts 64. It will therefore be clear that the movable contact 24 moves with and is controlled by the driven member 15. The fixed contacts 35 61 and 62 are connected to the wires 100 and 101, respectively, by their respective binding posts 102 and 103.

The operation of the parts so far described is as follows, it being understood that only 90 one driving member 25 is used: Suitable pressure upon the push button 36 bringing it from its elevated to its depressed position as shown in Fig. 2 will cause the driving member or nose piece 25 to move from the 95 upper wing 16 to the lower wing 16, assuming the position shown in Fig. 2. It is obvious that in this movement of the parts the driven member 15 will be caused to rock and disconnect the electrical connection by moving the arms 58 and 59 from their respective fixed contacts 61 and 62, the movable contact 24 being then in the position shown in Fig. 1. This downward movement of the push button 36 with its buttonholder 35 operating 100 on one side lever 20 through the ear 43 or an ear 44, will cause the corresponding button-holder and button to be elevated and assume the position shown in Figs 2 and 3. This will be true whether or not one or two 110 side levers 20 are used. It is therefore apparent that my mechanical movement will operate successfully simply with one driving member 25 and one side lever 20. The side lever or levers 20 move independently of the 115 driven member.

It has been found in practice that it is absolutely imperative for a successful electric switch that the make and break be exceedingly quick or rapid, to prevent arcing 120 at the contacts and the consequent burning out of the switch, with the resultant damage to the installation and possible damage to the house or other structure from fire. If the driving member 25 moves merely 125 upon a flat unbroken surface of the driven member it has been found in practice that when the nose 29 would pass the center of the driven member by even an infinitesimal distance there was a certain frictional drag 130

of the nose piece upon the driven member tending to cause it to rock slowly which of course would result in the moving contact approaching or receding, as the case may be, 5 to or from the fixed contacts at a relatively slow speed which resulted in arcing and the destruction of the switch. By my invention I eliminate this slow rocking of the driven member with the consequent relatively slow 10 movement of the moving contact by mounting a member at the center of the driven member so that it will take the thrust of the driving member when the driving member is at approximately the center of the driven 15 member, and also at a slight distance on either side of the center of said driven member. This will prevent the drag or frictional pull of the driving member on the driven member tending to slowly rotate it 20 and serves to store up power in the spring or resilient member of the driving member until such time as the nose 29 has reached an appreciable distance from the center of the driven member. 25 In the preferred construction, that shown for instance in Figs. 2, 4 and 15, I divide the driven member 15 into two portions or wings 16, 16 and mount a pin or axle 17 between them, the axle then being the center 30 of the driven member. It is apparent that as the driving member contacts with the axle 17, a further movement either up or down of the vertically reciprocating member 35 will, on account of the inclination of 35 the driven member cause the driving member 25 to be forced toward the buttonholder or vertically reciprocating member 35 and store up energy in the spring 26, until such time as the nose 29 passes the axle or pin 40 17 and contacts with the other wing 16, when the stored energy in the spring will be instantly released and will cause the driven member to be quickly rocked and consequently cause the movable contact of the 45 switch to quickly make and break with the fixed contacts 61 and 62. This is largely due not only to the fact that the frictional drag of the driving member on the driven member is eliminated when the nose 29 contacts with the pin or axle 17 but for the 50 further fact that the stored up energy in the spring is not permitted to act upon the driven member until the nose 29 has reached an appreciable distance from the center of 55 the driven member which permits the power being applied more advantageously due to a greater leverage on the driven member. The relative size of the axle or pin 17 and the wings 16, 16 may be varied to suit different conditions; obviously, if the diameter of the pin is increased the nose 29 would 60 operate upon the wings at a slightly increased distance from the center and consequently at an increased leverage. The 65 wings 16, 16 are entirely separate pieces of

metal and are separately assembled in the cartridge, the end pieces 4, 4 being opened slightly for this purpose, if necessary. After they have been seated, the pin 17 which is separate and distinct from the 70 wings 16, 16 is run through the apertures 14, 14 in the end pieces and between the respective wings, see Figs. 2, 4, 15 and 17.

While, as noted, I may use merely one driving member 25 I preferably use two such 75 members on opposite sides of the driven member as shown in the figures of the drawings. In some instances, though not necessarily, as my device will operate successfully without it, I may use an auxiliary spring 80 to operate in connection with either one or both of the vertically reciprocating members 35. In Fig. 2 I have shown a flat spring 67 having two arms 68, 68 lying in the path of the vertically reciprocating elements 35, 35 and which serves to assist them in their vertical upward movement. I may, however, use separate coiled auxiliary springs 69 such as shown in Fig. 20, though preferably these auxiliary springs are 90 omitted. These springs 67 and 69, when used, also act as buffers for the reciprocating member 35.

In addition to the elements above described I preferably, though not necessarily, 95 use a locking device to retard the rocking of the driven member, with its moving contact, until substantially the maximum amount of energy has been stored in the springs forming a part of the driving members and until the noses 29, 29 have reached a point upon the driven member, removed from the center, so that their stored up energy may be applied with substantially the maximum effect to insure a quick make and 100 break between the moving contact 24 and the fixed contacts 61 and 62. I preferably accomplish this purpose of retarding the driven member by means of a retarding plate 70 (Fig. 9) which is preferably 110 stamped out of sheet metal or other material and is provided with two angular escarpments 71, 71 which are preferably formed integral with the plate 70. One of these plates 70 is mounted upon the wings 115 16, 16 by passing their ends through the apertures 72, 72 in the plate and passing the pin or axle 17 through the center aperture 73 in the retarding plate. This arrangement insures the retarding plate 70 120 rocking with the driven member 15 and consequently with the moving contact 24.

The elongated ears 44, 44 (Fig. 12) cooperate with the escarpments 71, 71 of the retarding plate 70 (Fig. 3). When the parts 125 are in the position shown for instance in Fig. 3, if pressure is exerted upon the upper button 36 the buttonholder 35 connected to that button will of course move downward and will tend to carry with it the elevated 130

5 arm of the lever 20. The opposite arm of this lever 20, however, will raise the other buttonholder 35 and button 36 and with it the extended ear 44 which is confined to a vertical movement by the guide slot 49 in the cartridge. It is therefore obvious that 10 pressure upon the elevated arm of the lever 20 will cause the opposite buttonholder 35 with its elongated ear 44 to rise, the ear being so mounted as to engage on the interior of one of the escapements 71, and will 15 continue to so engage with that member until such time as the upward movement of the ear 44, with its holder 35 is forced out of engagement with the escapement 71 when instantly the driven member 15 will be violently or at relatively great speed thrown over or rocked into its opposite position, and with it the moving contact 24 making a 20 quick make.

The downward movement of the upper button 36 will in addition to rocking the lever 20, or two of them, if two are used, cause the driving member 25 carried by it to 25 move down past the center of the driven member 15 and tend to rock the driven member the moment that the nose 29 passes the axle or pin 17 and contacts with the lower wing 16. This tendency to rotate the driven member is, however, resisted by the elongated ear 44 engaging with the escapement 71, as noted, which engagement continues 30 until such time as the nose 29 has moved down the lower wing an appreciable distance when the ear 44 is forced out of engagement with the escapement 71 permitting the stored up energy in the driving member to be applied at the most advantageous position on the driven member which 35 will be at some distance from the center. This will insure a rapid make and break of the switch, it of course being understood that opposite movement of the button 36 which has just been elevated will reverse the 40 operation of the switch. In some instances I may place the escapements such as 71, 71 directly upon the moving contact plate 24, such escapements being shown in Figs. 22 and 23 and designated 73, 73.

45 By my invention I obtain a mechanical movement which is inclosed in a support or cartridge of minimum thickness and weight. The extreme shallowness of my switch permits it to be mounted in partitions without 50 extending inward a sufficient distance to interfere with sliding doors which may be mounted in the partition, and in any other location where a shallow switch is necessary or desirable. The shallowness of my 55 cartridge or container also permits the switch to be mounted in locations where little or no brick work has to be removed with the consequent saving in labor.

Attention is called to the fact that when 60 the parts of my mechanism are mounted in

my cartridge they are self-contained and are held in this position simply by means of the securing plate or bridge piece 12 (see Fig. 2). Furthermore the push buttons are not guided by a perforated bridge piece or face 70 plate. Such guiding mechanism is eliminated by my invention in that the guiding is done through the ears 43 and 44 operating in the guide slots within the cartridge. Furthermore my switch is not fastened to 75 the porcelain or insulating base by the aid of a bridge piece or any other separate element, but is held directly on the base plate or similar insulating support by means of the screws 9, 9 taking through the ears 8, 8 80 directly into the base, thus eliminating the additional cost of a separate bridge or similar plate with the additional cost of labor in assembling the parts. My switch can also be used as a convertible switch, such for instance as shown by U. S. Patent 872,432, patented December 3, 1907, to C. J. Klein.

It will also be noted that my locking mechanism when one is used, is simple, inexpensive, of few parts, and one element 90 is attached directly to the vertically reciprocating member or buttonholder whereas the other element (the retarding plate 70) is secured to the driven member 15. It will further be noted that all parts of my invention with the exception of the springs and the axle or pin 17 are formed from stampings which can be made at a minimum cost and can be readily assembled with the minimum amount of labor and time. This entire device is simple, small, compact, extremely shallow, cheap, light and entirely made of few and inexpensive parts.

Having thus described this invention in connection with the several illustrative embodiments thereof to the details of which I do not desire to be limited, what is claimed as new and what it is desired to secure by Letters Patent is set forth in the appended claims:

1. In a mechanical movement, the combination of one or more driving members adapted to have a sliding engagement with a driven member, means to reciprocate said member or members, and a rocking driven member having a flat surface and a separate member having a substantially round surface, said separate member being mounted to coincide substantially with the center of the flat surface of the driven member, said flat driven member being adapted to be operated by a sliding engagement with the driving member or members.

2. In a mechanical movement, the combination of one or more driving members, 125 means to reciprocate said member or members, a driven member formed of a plurality of parts independently mounted on separate bearings in a support, and a support provided with independent bearings for the dif- 130

ferent parts of the driven member, one of the parts being mounted substantially at the center of the driven member.

3. In a mechanical movement, the combination of one or more laterally movable driving members, a plurality of vertically reciprocating members carrying the laterally movable driving members, one driving member to each vertically reciprocating member, a support for said vertically reciprocating members, a driven member formed of a plurality of parts separately mounted upon the support, and one or more side levers carried by one of the parts of the driven member and adapted to have independent movement with relation to it, said side levers having an operative connection with the different vertically reciprocating members.

4. In a mechanical movement, the combination of a support provided with opposed sides, vertically reciprocating members carried by the support, one or more laterally movable driving members carried by the vertically reciprocating member or members, one to each vertically reciprocating member, a driven member mounted on the support, and one or more side levers mounted on the driven member, and means between the reciprocating member or members and the lever or levers permitting the reciprocating members to operate the lever or levers at different distances from the center of the lever or levers.

5. In a mechanical movement, the combination of a support provided with means to support a driven member, a driven member mounted on the support, vertically reciprocating members mounted on the support, means carried partly by the support and partly by the vertically reciprocating members to guide the latter, one or more laterally movable driving members, carried by the reciprocating member or members, one to each member, and one or more side levers pivotally mounted on the driven member and adapted to have independent movement with relation to it, and means slidingly connecting the vertically reciprocating members and the lever or levers.

50 6. In a mechanical movement a cartridge formed from stamped sheet material and bent up into its required shape and provided with guide and segmental slots, vertically reciprocating members mounted in the cartridge, one or more laterally and vertically movable driving members actuated by the vertically reciprocating members, guiding means on the vertically reciprocating members to coöperate with the guide slots in the cartridge, means to connect the vertically reciprocating members, and a driven member mounted in the segmental slots of the cartridge.

65 7. In a mechanical movement a cartridge formed from stamped sheet material and

bent up into its required shape and provided with guide and segmental slots and a bearing at the center of the same circle of which the segmental slots are a part, vertically reciprocating members mounted in the cartridge, one or more laterally and vertically movable driving members actuated by the vertically reciprocating members, guiding means on the vertically reciprocating members to coöperate with the guide slots in the cartridge, means to connect the vertically reciprocating members, and a driven member mounted in the segmental slots and in the center bearing of the cartridge.

8. In a mechanical movement, a cartridge formed from a stamped sheet metal and properly bent into shape, one or more driving members mounted in the cartridge and supported independently of the securing plate, a driven member supported independently of the securing plate, and a securing plate connecting the sides of the cartridge and at the same time securing within the cartridge the movable part of the mechanism.

9. A blank for making a cartridge for a mechanical movement, comprising a bottom piece, two integral side pieces, each provided with open straight slots and with closed segmental slots, each side piece being provided with an integral end piece.

10. A blank for making a cartridge for a mechanical movement comprising a bottom piece, two integral side pieces, each provided with open straight slots and with closed segmental slots, each side piece being provided with an integral end piece, said end pieces being oppositely disposed on the blank.

11. A blank for making a cartridge for a mechanical movement, comprising a bottom piece, two integral side pieces, each provided with open straight slots and with closed segmental slots, each side piece being provided with an integral end piece, said end pieces being oppositely disposed on the blank, and ears on the end pieces adapted to be bent out to form connecting means to secure the cartridge to a suitable support.

12. In a mechanical movement the combination of a cartridge stamped from sheet metal having guide and segmental slots and ends which with the sides of the cartridge form additional guide slots, one or more connected vertically reciprocating members formed from stamped metal and provided with ears and a lug to engage respectively with guide the slot in the cartridge and with the additional guide slot formed by the side and end of the cartridge, driving member or members carried by the vertically reciprocating member or members, and a driven member mounted in the segmental slots.

13. In an electric switch the combination

- of a support, two button holders mounted in the support, one or two driving members carried each by one button holder, a driven member formed of two wings provided with 5 cut away portions or recesses and a central pin or axle, one or more side levers mounted on the pin and within the recesses in the wings, means carried by the button holders to coöperate with the levers, a moving contact carried by the driven member and fixed contacts coöperating with the movable contact.
14. In an electric switch the combination of a support, two button holders mounted 15 in the support, one or two driving members carried each by one button holder, a driven member formed of two wings provided with cut away portions or recesses and a central pin or axle, one or more side levers mounted 20 on the pin and within the recesses in the wings, means carried by the button holders to coöperate with the levers, a moving contact carried by the driven member and fixed contacts coöperating with the movable contact, and a locking device carried partly by the button holder and partly by the driven member.
15. An electric push button switch, comprising a cartridge provided with guide 30 slots, two button holders and buttons having means to coöperate with the guide slots in the cartridge, and means to cause the button holders to reciprocate alternately, a driven member located between the button holders, one or more driving members carried by the 35
- button holders and adapted to coöperate with the driven member, and means on the support to secure it directly to an insulating base.
16. An electric push button switch, comprising a cartridge provided with guide slots and with ears, two button holders and buttons having means to coöperate with the guide slots in the cartridge, and means to cause the button holders to reciprocate alternately, a driven member located between the button holders, and one or more driving members carried by the button holders and adapted to coöperate with the driven member.
17. In a mechanical movement, the combination of a support provided with opposed sides, vertically reciprocating members carried by the support, one or more laterally movable driving members carried by the 50 vertically reciprocating member or members, one to each vertically reciprocating member, a driven member mounted on the support, and one or more side levers mounted on the driven member, and sliding means 55 between the reciprocating member or members and the lever or levers permitting the reciprocating members to slide upon the lever or levers and operate them at different distances from their center.

RALPH A. SCHOENBERG.
